UNITED STATES PATENT OFFICE.

CHARLES A. NEISWENDER AND WILLIAM C. WENTHE, OF TOPEKA, KANSAS.

CONVERTIBLE PORCH-SWING AND COUCH.

1,396,774.

Specification of Letters Patent.

Patented Nov. 15, 1921.

Application filed May 2, 1919. Serial No. 294,208.

To all whom it may concern:

Be it known that we, CHARLES A. NEISWENDER and WILLIAM C. WENTHE, citizens of the United States, residing at Topeka, in the county of Shawnee and State of Kansas, have invented certain new and useful Improvements in Convertible Porch-Swings and Couches, of which the following is a specification.

10 This invention relates to improvements in combined porch swings and couches, and an object of the invention is to provide a porch swing, in which end members are hingedly connected to the seat portion there-
15 of for movement into adjusted angular positions with respect to the seat to convert the swing into a couch and further to provide abutment members which are adjustably carried by the end members of
20 the swing and are adapted for engagement against the ends of the seat portion to maintain these hinged end portions in adjusted positions, such as one of them extending at an obtuse angle with respect to the seat
25 to form a pillow support for a user's head, while the other end portion may be substantially parallel to the seat portion.

Another object of the invention is to provide in a convertible porch swing and couch
30 as specified, notches or recesses in the ends of the arm rests of the end members which receive therein chains or flexible suspending means of the swing, for maintaining the end members in vertical positions.

35 A still further object of the invention is to provide a convertible porch swing and couch as specified, which may be readily knocked down or taken apart, for packing, storage or shipping, the end members and
40 back rest being connected to the seat by means of bolts and wing nuts, whereby by the removal of the wing nuts, the various sections may be disconnected and packed in abutting engagement with each other to pro-
45 vide a compact structure.

Other objects of the invention will appear in the following detailed description, taken in connection with the accompanying drawings, forming a part of this specification,
50 and in which drawings:

Figure 1 is a perspective view of the improved convertible porch swing and couch showing the end members in vertical positions and the device adjusted as a porch swing.
55

Fig. 2 is a perspective view of the con-

vertible porch swing and couch showing the end members adjusted to provide a couch.

Fig. 3 is a vertical cross section through the convertible porch swing and couch when the end members are adjusted as illustrated in Fig. 1.

Fig. 4 is a fragmentary longitudinal section through one end member and adjacent end portion of the seat showing the end member in horizontal position, and

Fig. 5 is a fragmentary view illustrating one of the end members in an angularly adjusted position to form a pillow rest or support.

Referring more particularly to the drawings, 10 indicates the seat portion of the convertible swing and couch which is made up in the usual manner of constructing the seat portion of porch swings, namely comprising 75 end members or bars 11 and a front bar or riser 12 to the upper edges of which the seat slats 13 are attached. The back rest 14 is also constructed in the usual manner of forming back rests for porch swings, it comprising upper and lower longitudinally extending bars 15 and end bars 16. Slats or boards 17 are attached to extend between the longitudinal bars or boards 15. However this particular construction, and the particular construction of the seat forms no part of the present invention, and it is to be understood that the back rest may be made in any approved manner without departing from the spirit of the invention.

90 The end bars 16 of the back rest structure extend downwardly below the lower longitudinal bar 15 and their lower ends are seated in recesses formed in the inner side of the end members of supporting bars 18. 95 The supporting bars or strips 18 are attached to the end strips 11 of the seat structure 10 by means of bolts 19 and wing nuts 20, so as to permit disconnection between the ends of the supporting strips 18 and seat structure 100 10 if desired, when packing the convertible swing and couch for storage or shipment. The end strips or bars 16 of the back rest structure 14 are also connected to the end member supporting strips 18 by means of bolts 21 and wing nuts 22, to permit the ready disconnection of these members when it is desired to collapse the swing structure for storage or shipment.

110 The end members 23 and 24 of the swing are hingedly connected, by means of hinges 25' to their supporting strips 18 in such

manner as to allow the said end members to be swung outwardly into inclined or horizontal positions as shown in Figs. 2, 4 and 5 of the drawings. Abutment members 25 are connected to the uprights or side rails 26 of each of the end members 23 and 24, by means of bolts 27 which extend through slots 28 formed in the uprights 26, permitting slideable movement of the abutment members upon the end members, for regulating the engagement of the abutment members with the outer edges of the strips 18, for supporting the end members in adjusted positions. For example, when it is desired to support one of the end members at an oblique angle with respect to the seat 10, for the purpose of supporting a pillow or forming a head rest, the abutment members upon the said member are adjusted, so that their inner ends will project beyond or below the inner end of the end members; thus when the end member is swung outwardly upon its hinged connection with the strips 18, the inclined surface 29 of the abutment members which are carried by the said end member will engage against the outer surface of the supporting strip 18 and form a surface contact with the supporting strip 18 to support the hinged end members in their angularly adjusted position. However, when it is desired to support the hinged end member in a horizontal position, the abutment members 25 carried thereby, are moved longitudinally so that their lower ends will be substantially flush with the lower ends of the end member; thus when the end member is lowered into a horizontal position, as shown at the right in Fig. 2 and in Fig. 4, the flat surface 30 on the lower ends of the abutment members will engage against the outer side of the supporting strip 18, forming surface contact therewith for supporting the said end member in a horizontal position.

Wing nuts 31 are mounted upon the bolts 27 for holding them in adjusted positions, and suitable washers or collars 32 are mounted in the abutment members to prevent mutilation of the said abutment members by adjustment of the wing nuts 31.

The convertible porch swing and couch is suspended, by the usual form of chains or analogous flexible members indicated at 32 and these chains or flexible members are connected, through the medium of eye bolts 33 with the end supporting strips 18, one at each end of each of the supporting strips as clearly shown in the drawings. The arm rests 33 of the end members are provided with concaved portions or recesses as shown at 34 in their ends which are adapted to receive the chains or flexible supports 32 therein, to maintain the end members 23 and 24 in upright or vertical positions against accidental outward and downward swinging movement. The arm rests 33 are

also provided with notches 35 in their inner edges which engage over the end strips 16 of the back rest 14 when the end members are in upright or vertical positions, thus securely connecting and bracing all of the parts of 70 the swing.

Changes in details may be made without departing from the spirit of this invention, but;

I claim:

1. In a convertible porch swing and couch, the combination of a seat, transverse end bars rigid therewith, end members hingedly connected to the said end bars of said seat, means for retaining said end members in an 80 upright position with respect to said seat, and abutment members carried by said hinged end members for engagement against the end bars to support said end member when swung to another position, 85 with respect to said seat, independent of said first mentioned means.

2. In a convertible porch swing and couch, the combination, of a seat, end members hingedly connected to the seat, and abutment members adjustably carried by the hinged ends, said abutment members adapted to be adjusted to present different surfaces for engagement against the ends of said seat to support the end members in 95 various adjusted positions.

3. In a convertible porch swing and couch, the combination, of a seat, end members hingedly connected to said seat, abutment members adjustably carried by said end members, said abutment members having angularly disposed flat portions on their lower ends adapted for engagement against the ends of the seat to support said end members in adjusted positions.

4. In a convertible porch swing and couch, the combination, of a seat, end members hingedly connected to said seat in a manner to swing outwardly from the ends thereof, abutment members adjustably carried by 110 said end members, said abutment members having angularly disposed flat portions on their lower ends adapted for engagement against the ends of the seat to support said end members in adjusted positions, suspending chains for said swing, said end members including arm rests having recesses in their ends for engaging said chains to maintain the end members in vertical position.

5. In a convertible porch swing and couch, 120 the combination, of a seat, end members hingedly connected to the seat in a manner to swing outwardly from the ends thereof, abutment members carried by the hinged ends for engagement against the ends of the 125 seat to support said hinged end members in various adjusted positions with respect to the seat, arm rests upon said end members and having recesses in their ends, and suspending chains for said swing, said chains 130

adapted for engagement in the recesses in said arm rest to maintain the end members upright.

6. In a convertible porch swing and couch, 5 the combination, of a seat, end members hingedly connected at their lower end portions to the seat in a manner to swing outwardly at the end of the swing, suspending chains for said swing, and arm rests carried 10 by the upper portions of said end members, said arm rests having recesses in their ends for engaging said chains to maintain the end members upright.

7. In a convertible porch swing and couch, 15 the combination, of a seat, supporting strips detachably connected to the ends of said seat, a back rest detachably connected to said strips, suspending chains for said swing detachably connected to 20 said strips one at each end of each strip, and end members hingedly connected to said supporting strips, abutment members adjustably connected to said end members for 25 slideable movement with respect to the end members, said abutment members adapted to be adjusted to present different surfaces for engagement against the ends of said seat

to support the end members in various adjusted positions.

8. In a porch swing, the combination of 30 a seat having transverse end bars, a back rest, end members having bars at their lower portions, flexible members connected with the bars of said end members for supporting the swing, means detachably connecting 35 the lower portion of said back rest to said bars of said end members, and means detachably connecting said end bars of said seat to the said bars of said end members.

9. In a porch swing, the combination of 40 a seat having transverse end bars, a back rest, end members having bars at their lower portions, flexible members connected with the bars of said end members for supporting the swing, means detachably connecting 45 the said end bars of said seat to the said bars of said end members, and means detachably connecting the lower portion of said back rest to said bars of said end members with the lower end portion of the back 50 rest engaging the ends of the bars of said seat.

CHARLES A. NEISWENDER.
WILLIAM C. WENTHE.
